UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

REFRIGERATOR-CAR-DOOR-OPERATING MECHANISM.

Application filed January 21, 1924. Serial No. 687,528.

This invention relates to improvements in refrigerator door operating mechanisms.

One object of the invention is to provide a simple and efficient arrangement of door

5 operating mechanism, especially adapted for refrigerator cars, for forcing the doors to tightly closed position for holding the same closed, and which will also be effective in starting the door opening operation.

10 A more specific object of the invention is to provide a mechanism of the character indicated, especially designed for operating doors of the swinging type, including a rotary operating shaft having an offset portion functioning as a door operating crank arm adapted to coact with a fixed keeper secured to the door framing.

Other objects and advantages of the invention will more clearly appear from the 20 description and claims hereinafter following.

In the drawings forming a part of this specification, Figure 1 is a side elevational view of a portion of a refrigerator car, showing my improvements in connection therewith.

25 Figure 2 is an enlarged, vertical sectional view, partly broken away, corresponding substantially to the line 2—2 of Figure 1. Figure 3 is a horizontal, sectional view, corresponding substantially to the line 3—3 of Figure 1. And Figures 4 and 5 are horizontal, sectional views through one of the offset end portions of the operating shaft taken along the lower edge of the right hand door, Figure 4 showing the position of the parts 30 when the doors are completely closed and Figure 5 showing the position of the parts with the right hand door partly closed.

In said drawing, the car is shown as provided with a door frame 10 and two pivoted 40 doors 11 and 12 having meeting beveled edges in the usual manner. As is customary in refrigerator cars, insulation or packing is employed between the meeting edges of the doors themselves and around the sides and top. 45 The doors 11 and 12 are mounted to swing about vertical axes, being supported by suitable hinges 13.

As shown, the improved door operating mechanism comprises broadly, an operating 50 shaft A provided with two end castings B—B and an operating handle C; upper and lower keepers D—D coacting with the castings B; and a pair of upper and lower bearing brackets E—E.

The operating shaft A is in the form of a 55 flat bar of rectangular cross section having the handle or lever C pivoted thereto by a pin 21.

The castings B are disposed respectively at the upper and lower ends of the shaft A. 60 Each of the end castings B, as shown, is preferably in the form of a crank having a cylindrical journal portion 22 alined with the axis of the operating shaft and an offset cylindrical end portion 23 or crank arm which 65 latter also serves as a journal section as hereinafter described. Each casting B is formed with a head 24 at the outer end of the journal portion 22, vertically slotted as indicated at 25 to receive the corresponding end of the 70 shaft A, to which it is fixed by rivets 26 or any other suitable form of securing means. At the opposite end of each casting B, projecting laterally from the free end of the offset portion 23, are a pair of diametrically opposed, 75 horizontally disposed lugs 27 and 28 offset 90° from the plane of the crank portion 23. The lug 28 is equal in width to the diameter of the portion 23, while the lug 27 is of approximately half the width of the lug 28 and 80 is disposed to one side of the vertical axis of the crank arm 23, having its inner edge 29 radially disposed thereto. The free end of the lug 27 is beveled as indicated at 31. The surfaces 29 and 31 together constitute a cam 85 member adapted to coact with the corresponding keeper D. At the inner end of the lug 27, the crank 23 is vertically recessed as indicated at 32, providing a concave cam face forming a continuation of the straight face 90 29.

The bearing brackets E—E, which are of like construction, are respectively mounted at the upper and lower ends of the door 11 adjacent the free edge thereof. Each of the 95 brackets E comprises a housing provided with a pair of oppositely disposed flanges 33 by which the bracket is bolted to the door. The housing of each bracket is defined by a vertically disposed wall 34 and a horizontally disposed wall 35, the wall 34 having spaced parallel side sections and a curved outer section. The walls 35 of the two brackets E respectively form closures for the top of the lower housing and the bottom of the upper 100 housing. Each wall is provided with a boss 36 having a bearing opening 37, elongated parallel to the door, the openings 37 of the two

5   housings being vertically alined and each adapted to rotatably and reciprocatingly receive the corresponding bearing portions 22 of the shaft. At the bottom of the lower bracket E and at the top of the upper bracket E, each 10 is provided with an additional bearing slot 50 elongated perpendicularly to the door. It will be noted that the brackets EE in conjunction with the crank portions of the shaft 10 afford a camming action which serves to positively cause lateral bodily travel of the shaft with reference to the door when the shaft is rotated.

15   The upper and lower keepers, which are mounted on the lintel and threshold of the door frame are of substantially similar construction, each comprising a vertically disposed, plate-like portion 38 by which the keeper is bolted to the car. Each plate 38 is 20 provided with outwardly projecting, horizontally disposed, upper and lower spaced flanges 39—39. Each keeper is also provided with a slot 40 disposed parallel to the side wall of the car, open at the left hand end as seen in 25 Figures 1, 4 and 5 of the drawing, and adapted to receive the corresponding lug 27 of the shaft A. The slot 40 of each keeper is defined by a vertically disposed web 41 extending between the flanges 39 and a relatively thick 30 wall 42 having its outer face beveled and its end rounded.

35   The plate portion 38 of the lower keeper D is extended to the left as seen in Figure 1, beyond the free edge of the door 11 and has pivotally mounted thereon a latch member 43 adapted to coact with a plate 44 secured to the door 12 adjacent the lower outer corner thereof. The latch 43 serves to retain the door 12 in position when closed.

40   The handle C is adapted to be locked as shown in Figure 1 by any suitable latch device as indicated at 45 and sealed in any suitable manner.

45   In operation, my improved mechanism works as follows, assuming the doors in closed position and that it is desired to open the doors. With the doors closed, the lugs 27 are in the position best indicated by Figure 4, and, as the shaft is rotated in a counter-clockwise 50 direction through the handle C, the lugs 27 will first cooperate with the walls 41, thus forcing the centers of the journal or crank arm sections 23 of the shaft outwardly away from the door frame. During this action, the 55 journal sections 22 of the shaft will move to the left in the elongated bearings 37, as viewed in Figure 3, and it will be obvious that the door 11 is thereby gradually forced outwardly. As the rotation of the shaft continues in 60 the manner described, the lug 28 will thereafter engage the inclined cam faces 51—51, of the brackets D (see Fig. 5) and the axis of the crank arm or journal sections 23 will be still further moved outwardly away from the door 65 frame and the door 11 consequently further

opened. At this point, attention is directed to the fact that the opening throw of the door is augmented due to the combined throw obtained by the lugs 27 plus the additional throw caused by lugs 28 traveling along the 70 inclined bearing faces 51 above referred to. This is of importance since, with a given offset of the crank arm sections 23 relative to the journal sections 22 or center line of the main part of the shaft, I am enabled to obtain an 75 opening movement which is in excess of double the offset of the crank arm sections 23 and hence positively insure that the free edge of the door 11 will clear and be fully released from the free edge of the other door 12. 80 As soon as this movement above described has taken place, it is evident that the door 11 can then be readily swung to fully opened position and the door 12 thereafter opened by releasing the latch 43.

85   The shaft A being first disposed in the position shown in Figure 5, the door 11 is slammed. This will bring the lug 28 into violent engagement with the face 51, which will tend to rotate the shaft A partially in a 90° closing direction, bringing the lug 27 around into position to enter the slot 40, whereupon closing of the door is completed by rotating the operating shaft by means of the handle lever C, the various portions of the mechanism assuming the full line position shown in Figures 2 and 4.

90   By referring to Figure 3, it will be noted that the elongated bearing openings 37 in the brackets E are elongated to both sides of the main axis of the shaft as viewed in said figure, although the shaft never moves into the righthand part of said elongated openings. This is done to enable me to use the same pattern for both brackets E for top and bottom. 100 It will also be noted that the brackets E are made each as a single piece to reduce the number of parts and said brackets are assembled with the shaft, as follows. A bracket E is applied, for instance, to the lower end 110 of the shaft, with the elongated bearing opening 37 parallel to the lugs 27 and 28 and the latter inserted through the elongated bearing opening 37. After the lugs are passed through said bearing opening, the bracket is 115 given a 90° turn which then brings the lugs 27 and 26 in alinement with the lower bearing opening 50, through which said lugs may then be dropped, thus leaving the offset portion between the journal sections 22 and 23 120 housed in the bracket E between the upper and lower bearing openings 36 and 50.

125   I have herein shown and described what I now consider the preferred manner of carrying out my invention but the same is merely illustrative and I contemplate all changes and modifications that come within the scope of the claims appended hereto.

I claim:

1. In a door operating mechanism, the com- 130

bination with a member having a door opening and a pivoted door; of a keeper fixed to said member adjacent the door opening, said keeper being provided with an elongated slot; 5 an operating rotary shaft mounted on the door; means for rotating the shaft; means for effecting bodily movement of the shaft transversely of the door when rotated; and eccentric means on said shaft co-acting with the 10 slot of said keeper for effecting movement of the door, said means being moved eccentrically to the shaft while partaking of the bodily movement of the shaft.

2. In a door operating mechanism, the combination with a member having a door opening and a pivoted door; of a rotary shaft journaled on said door and bodily movable therewith; a keeper fixed on said member; eccentrically disposed elements on said shaft, 20 said elements successively coacting with said keeper to effect movement of the door upon rotation of the shaft.

3. In a door operating mechanism, the combination with a member having a door opening and a pivoted door; of a rotary operating shaft supported on the door, a crank arm on said shaft; means co-operating with the crank arm for imparting movement to the shaft bodily transversely along the door when rotated; a cam element on said arm; and keeper means fixed on said member engageable by the cam element for effecting movement of the door upon rotation of said shaft.

4. In a refrigerator car having a pivoted side door, the combination with an operating shaft mounted on said door, said shaft being bodily movable with the door and provided with a crank portion; a pair of cam elements on said crank portion; a bearing on the door 40 for said shaft; a keeper fixed to the car, said keeper having a plurality of faces adapted to coact respectively with said elements to effect movement of said shaft and door upon rotation of the shaft.

5. In a refrigerator car, the combination with a pivoted side door; of a shaft journaled on said door and bodily movable therewith; a pair of eccentrically disposed elements on said shaft; and a keeper fixed to the car, said 50 keeper having a plurality of faces adapted to be successively engaged by said elements upon rotation of said shaft to effect movement of the door.

6. In an operating mechanism for a door mounted on a door frame, the combination with an operating shaft having relatively offset journal sections at each end, the extreme ends of said shaft projecting beyond the corresponding edges of the door; of bearing brackets on the door, each bearing bracket having an elongated bearing opening for each of the journal sections at the corresponding end of the shaft, said bearing openings being extended at right angles to each other; and keepers secured to the door

frame and each cooperable with one of said extreme extended ends of the operating shaft, each keeper and corresponding extreme end of the shaft having cooperating engageable shouldered portions effective to positively 70 cam the door to final closed position when the shaft is operated in one direction and to positively cam the door to partially opened position when the shaft is rotated in the opposite direction. 75

7. In an operating mechanism for a door mounted on a door frame, the combination with an operating shaft having relatively offset journal sections at each end, the extreme ends of said shaft projecting beyond the corresponding edges of the door; of bearing brackets on the door, each bearing bracket having an elongated bearing opening for each of the journal sections at the corresponding end of the shaft, said bearing openings being 80 extended at right angles to each other; and keepers mounted on the door frame to cooperate with the respective extreme projected ends of the operating shaft, said keepers and projecting extreme ends of the shaft having 85 cooperating means operative in an opening movement of the door to effect an opening movement greater than twice the offset of said journal sections of the shaft.

8. In an operating mechanism for a door pivotally mounted in a door frame, the combination with an operating shaft having a crank arm section at one end thereof projecting beyond the corresponding edge of the door; of means for attaching said shaft to 100 the door, said means being provided with bearing openings permitting rotation and also bodily shifting of said shaft with respect to the door while being rotated; a keeper secured to the door frame in line with the shaft and arranged to cooperate with said projected end of the shaft; and cooperating engageable means on said keeper and projected end of the shaft adapted, upon rotation of the shaft, to force the door in an opening direction, said means having a cumulative camming action effective to produce an opening movement in excess of twice the offset of said crank arm section with respect to the remainder of the shaft. 110

9. In a door operating mechanism, the combination with a member having a door opening and a pivoted door; of a keeper fixed to said member adjacent the door opening; a rotary operating shaft adapted to have mounting means associated therewith for attachment to said door; means co-operating with said shaft and said mounting means providing cam means for imparting bodily movement to said shaft upon rotation thereof; and a plurality of eccentrically disposed members on said shaft, said members being arranged to successively co-act with said keeper to effect movement of the door upon operation of the shaft. 125

10. In a door operating mechanism, the combination with a member having a door opening and a pivoted door; of a keeper secured to said member adjacent the door opening; an operating shaft rotatably mounted on the door and having a portion thereof offset; means co-operating with said off-set to effect travel of the latter transversely along the door while rotated, and means on said off-set portion co-acting with said keeper to effect movement of the door upon rotation of said shaft.
11. In a door operating mechanism, the combination with a member having a door opening and a pivoted door; of an operating shaft rotatably mounted on said door and having an off-set; a keeper fixed on said member; means having cam slots for the reception of said off-set to effect a camming action therebetween upon rotation of said shaft to impart bodily movement to said shaft; and
- keeper engaging means operated by the rotation and bodily movement of the shaft.
12. In a door operating mechanism, the combination with a member having a door opening and a pivoted door; a rotary operating shaft; means on said shaft and door for effecting travel of a portion of said shaft bodily relative to said door; additional means extending at an angle to said shaft and adapted to be rotated thereby; and a keeper fixed to said member and co-acting with the bodily movable portion of said shaft and said additional means, whereby the combined bodily displacement of said portion and rotational movement of said additional means is effective in imparting movement to said door.

In witness that I claim the foregoing I have hereunto subscribed my name this 18th day of January, 1924.

STACY B. HASELTINE.
